UNITED STATES PATENT OFFICE.

ANTON A. SCHOENECK, OF SAN FRANCISCO, CALIFORNIA.

RICE SEPARATOR.

Application filed February 20, 1926. Serial No. 89,719.

My said invention relates to a separating device intended primarily for cleaning rice by removal of water grass seed from the same. While designed particularly for the cleaning of California paddy rice, it may obviously be used for cleaning other grains and seeds as well as for separation of fluent solids having granules of different sizes or otherwise different in their characteristics.

10 This invention is an improvement on the machine shown in my Patent No. 1,523,906, January 20, 1925, and it is an object thereof to increase the capacity of the machine and improve the results obtained.

15 Referring to the accompanying drawings which are made a part hereof and on which similar reference characters indicate similar parts.

Figure 1 is a front elevation of the device 20 of my invention,

Figure 2, a side elevation,

Figure 3, a longitudinal section,

Figure 4, a transverse section on line 4—4 of Figure 3,

25 Figure 5, a longitudinal section on an enlarged scale, this view being similar to Figure 3 but omitting some of the parts,

Figure 6, a transverse section of the drum and parts above the same,

30 Figure 7, a top plan of a shield shown in Figures 4 and 6, and

Figure 8, a plan of a screen located above the revolving drum.

In the drawings reference character 10 35 indicates a revolving drum mounted for rotation in bearings 11. Antifriction bearings are provided at 12 between the bearings and the end pieces 13 and 14 of the drum. These end pieces are imperforate 40 whereas the remainder of the drum consists of perforated sheet metal the openings being small enough to exclude rice or other material which is being cleaned but permitting the passage of water grass seed, dust, 45 and other small impurities. The drum is driven in the direction indicated by the arrows by means of a belt 15 passing about the end piece 13 of the drum, and driven from any suitable source of power (not 50 shown).

The drum is mounted in a suitable casing 16 provided at its lower side with hoppers 17 and 18. The casing 16 communicates at its upper end with a storage cham-

ber 20 provided at its lower end with a 55 suitable feeding means, such as a longitudinally grooved roller 21 for feeding the material to be cleaned in a regular flow from the storage chamber to the casing. The roller 21 is driven in suitably timed 60 relation with the remaining parts of the device.

A screen 22 is supported above the drum for oscillation about the axis of the drum. The screen may be supported on arcuate 65 bearings extending from the sides of the casing 16 or in any other suitable manner. For oscillating the screen I have provided gears 23 having teeth meshing with the teeth of rack segments at the ends of the screen. 70 These gears are fixed to a shaft 24 for rotation therewith and said shaft driven by means comprising a rock-arm 25 fixed to the shaft, a link 26, and a crank disk 27 on a shaft 28 carrying a pulley 29 driven 75 by a belt 30.

Within the drum and covering an arc extending approximately two-fifths ($\frac{2}{5}$) of the way around the drum at the lower side thereof is a shield for cutting off the suction from this part of the drum, said shield consisting of a body 31 which may be of sheet metal and which is provided at one side with a strip 32 of rubber or other suitable yielding material which prevents the 80 entrance of air between the edge of the member 31 and the corresponding inner face of the drum. At the opposite side of this shield I have mounted thereon a brush 33 extending over the entire length of the drum 85 and serving to clean the drum by freeing the holes from material which might otherwise clog the perforated cylinder and interfere with the operation of the machine. The suction-interrupting device is supported as 90 illustrated in Figure 5 with its ends abutting against the outer sides of recesses in the bearings 11.

The bearings 11 are provided with annular flanges at 34 extending axially outward from the drum and serving to support flanges forming parts of pipes 35 and 36, which extend upward and then converge above the casing 16 where they unite with a pipe 37 leading to a fan casing 38. 100 This casing has an outlet pipe 39 through which the water grass seed and other refuse of small size are carried away to a suitable

collection device, as shown in my former patent above referred to, or are otherwise disposed of.

In the operation of my device the grain or other material to be separated is fed from the container 20 into the casing 16 and is agitated by the screen 22 which is constantly oscillated due to the rotation of the shaft 28 which reciprocates the pitman 26 and oscillates the rock-arm 25, the gear 23, and therefore the screen 22. This oscillation coacts with the clockwise rotation of the drum 10 to feed the grain in a thin layer in a clockwise direction about the axis of the drum. The openings in the drum are so proportioned that water grass seed and other small impurities will be drawn through them by the suction of the fan in the casing 38 acting at both ends of the drum to draw the air through the perforations in the drum and therefore to draw with it any impurities which are sufficiently light and small to be influenced by the air current. The grain which is of larger size than the impurities passing through the openings moves around with the drum and falls into the hopper 17.

Without the screen 22 the rice and water grass seed with beards would hold to the cylinder till they had passed over above the hopper 17. This screen's purpose is to give the suction more chance to pull the water grass seed with beards through the holes. If a water grass seed with its beard lays across the holes the suction cannot pull it through, but with a screen 22 present the water grass seed is upset and brought into many different positions so that the suction has a chance to pull it through end ways.

The impurities of large size and light weight, such as bearded seeds and parts of heads of rice, are held to the surface of the drum until they pass the hopper 17 and reach the segment in which the suction is cut off by the shield 31, whereupon they fall into the hopper 18 and are carried away thereby. In this way it will be seen that in a single operation the grain is cleared both of small refuse such as weed seeds and of large refuse such as bearded seeds and the like. By the use of a suction device acting at both ends of the drum a more effective cleaning action is had as the suction acting through the openings in the drum is much stronger than in my previous device. It is also found of advantage to substitute the screen 22 for the feeding mechanism previously in use and to collect the cleaned grain at the right-hand side while permitting the large and light refuse to pass on to the left-hand side of the drum.

It will be obvious to those skilled in the art that my device may be changed in various respects, and therefore I do not limit

myself to what is shown in the drawings and described in the specification but only 65 as indicated in the appended claims.

Having thus fully described my said invention, what I claim as new and desire to secure by Letters Patent is:

1. A separating device for grain and the like comprising a rotary perforated drum, means for supplying material to be cleaned to the upper surface of the drum, a device adjacent the periphery of the drum mounted for oscillation about the axis of the same 75 to stir the material as it proceeds in the direction of rotation of the drum, means for driving said device, means for producing a suction in the drum, means for collecting the cleaned grain, and means for cutting off the suction about a segment of the drum, substantially as set forth.

2. In a separating device for grain or the like, a rotary suction drum having perforations for the passage of minor impurities, 85 means for feeding the material to be cleaned to the upper side of the drum, and mechanical agitating means close to the outer periphery of the drum, substantially as set forth.

3. A device as in claim 2, said agitating means oscillating about the axis of the drum, substantially as set forth.

4. In a separating device for grain and the like, a perforated drum, means for passing material to be acted on over the surface of the drum, mechanical stirring means adjacent the outer surface of the drum, and means operating at both ends of the drum to create a suction therein, substantially as set 100 forth.

5. A separating device for grain or the like including a rotary perforated drum, an oscillating screen adjacent thereto, a casing having walls fitting against the surface of the drum adjacent opposite ends thereof, fixed bearings having recesses to receive the ends of the drum, anti-friction devices in said recesses for supporting the drum, and a driving belt engaging the drum between 105 a wall of the casing and one of said bearings, substantially as set forth.

6. In a separating device for grain or the like, a rotary drum having perforations for the passage of minor impurities, means for feeding the material to be cleaned to the upper side of the drum, an arcuate screen close to the periphery of the drum, and means for oscillating the screen, substantially as set forth.

In witness whereof, I have hereunto set my hand at San Mateo, California this 10th day of December, A. D. nineteen hundred and twenty-five.

ANTON A. SCHOENECK.
